Term of patent 14 years

Int. Cl. D9—01

U.S. Cl. D9—9

FIG. 1.

FIG. 2.

FIG. 3.

FIG. 5.

FIG. 6.

FIG. 4.

FIG. 1 is a front elevational view of a dispensing container embodying my new design;

FIG. 2 is an elevational view looking from the right of FIG. 1 with portions broken away for convenience of illustration;

FIG. 3 is a fragmentary rear elevational view;

FIG. 4 is a top plan view on an enlarged scale;

FIG. 5 is a fragmentary isometric view on an enlarged scale showing the upper end; and

FIG. 6 is a fragmentary, isometric view on an enlarged scale showing the upper end with the spoutlike closure in an open position.

The dominant features of my design reside in the portions shown in full lines.

I claim:

The ornamental design for a dispensing container, substantially as shown and described.
